UNITED STATES PATENT OFFICE.

JOHN W. SEIFERT, OF PRATTVILLE, ALABAMA.

PNEUMATIC GIN-FEEDER.

No. 804,888.

Specification of Letters Patent.

Patented Nov. 21, 1905.

Application filed August 9, 1904. Serial No. 220,130.

To all whom it may concern:

Be it known that I, JOHN W. SEIFERT, a citizen of the United States, residing at Prattville, in the county of Autauga, State of Alabama, have invented certain new and useful Improvements in Pneumatic Gin-Feeders, of which the following is a specification, reference being had therein to the accompanying drawings.

10 This invention relates to a pneumatic gin-feeder, and particularly to a structure for elevating, cleaning, and feeding seed-cotton to gins.

15 The invention has for an object to provide a construction whereby the screening-rollers and picker-rolls are spaced from each other and intermediate thereof feed-rollers are disposed in air-tight contact, so as to form a suction-chamber in the upper portion of the casing and a delivery-chamber below said rollers, within which the picker-roll operates, thus providing a machine occupying the minimum of space and having a continuous suction-feed by which the cotton is twice cleaned and the 25 use of the ordinary trip-valve, switch, or release-valve for the purpose of releasing the cotton from the suction entirely obviated.

20 The invention also dispenses with the necessity of using a canvas or flexible valve, as in many instances, to retain the cotton until the amount collected is sufficient to be released by an air-cut-off valve, and the cleaning action is performed entirely within the machine.

25 A further object of the invention is to provide a novel construction and arrangement of the gearing for driving the several movable parts of the device and for permitting a movement of the feed-rollers toward and from each other while under operation.

30 Other and further objects and advantages of the invention will be hereinafter set forth and the novel features thereof defined by the appended claims.

35 In the drawings, Figure 1 is a central vertical section through the machine on the line 1 1 of Fig. 2. Fig. 2 is a central longitudinal section on the line 2 2 of Fig. 1. Fig. 3 is an end view showing the gearing. Fig. 4 is a similar view of the opposite end of the machine. Fig. 5 is a detail horizontal section on the line 5 5 of Fig. 3, and Fig. 6 is an elevation showing the arrangement of a plurality of the feeders.

40 Like letters of reference refer to like parts in the several figures of the drawings.

45 The letter A designates a casing or inclosure

of any suitable material, preferably metal, and is connected at its top or upper portion with a cotton-feed pipe A', which is provided with a communicating opening A², which communicates with the throat A³ of the feeder. The end of the cotton-pipe A' is provided with the usual suction-feed connection at A⁴, as shown at the broken-away portion in Fig. 6. The casing also communicates at one end A⁵ 65 with a suction-pipe A⁶, connected to each of the feeders in a series thereof and extending to a suction-fan A¹¹, driven in any suitable manner, as indicated in Fig. 6. The casing is provided at the opposite side from the suction-pipe A⁶ with a delivery-trough A⁷, pivotally mounted at A⁸, so as to be vertically adjustable to different characters of gins for feeding the cotton from the casing into the gin, Figs. 1 and 4. The cotton-pipe A' may, if 75 desired, be provided with a suitable glazed or transparent aperture A⁹ for the inspection of the contents thereof, and similar windows or openings may be located at any desired part of the casing, as indicated at A¹⁰, opposite a 80 drum.

85 The throat A³ has disposed at one side thereof a cut-off valve B, pivotally mounted at B' beneath the cotton-pipe A', so as to shut off the feed of material when the feeder is out of use. For the purpose of operating this valve an arm B² is provided, and an operating-handle B³ extends therefrom to a convenient position for the operator. Beneath the cut-off valve B a screen-valve C, formed in two parts 90 pivotally mounted at opposite sides of the throat A³, is provided for the purpose of temporarily stopping the feed of cotton to the screening-drums—as, for instance, between different lots thereof. The pivots C' of the 95 screen-valves are each provided with a segmental gear C², meshing with each other and operated in unison by means of an arm C³ and operating-handle C⁴. At the delivery from the throat A³ the oppositely-disposed screening-drums D are rotatably mounted, each being disposed beneath a partition D', which is provided with a wiper D², contacting with the drum, so as to secure air-tight contact at the upper portion thereof, while within each of the drums is a shield or cut-off plate D³ to prevent the suction action at the lower part of the drum, and thus release the cotton carried by the drum directly above the feed-rollers E. These shields D³ extend concentric with the face of the drum D and are pivotally mounted upon inwardly-extending stub-shafts D⁴, so as to 100 105 110

leave the interior of the frame free from obstruction to receive the full suction action where the end of the drum communicates with the pipe A⁶, which surrounds the openings A⁵.
 5 The space between the two suction-drums is suitably closed by a plate D⁵, so that the dust and dirt carried by the cotton is effectually removed by the suction through the drums and carried to the fan, while the cotton ad-
 10 hering to the surface of the drum is discharged as the drum passes over the surface of the shield D³. Beneath the outer portion of each of the drums is a horizontally-disposed parti-
 15 tion D⁶, which acts as a baffle-plate to prevent any suction action at this point which would disturb the feed of material in the lower part of the casing.

The feed-rollers E are each provided with journals or shafts E', mounted in slotted open-
 20 ings E² in the casing, said slots lying in arcs having their centers at the axes of the screening-drums above the feed-rollers. Each of the rollers may be covered with any suitable covering of canvas, rubber, or other material
 25 for the purpose of securing the proper contact with each other and preventing the escape of air between the same, while they are normally held at each end under tension in such contact by means of the spring E³, extending from
 30 the journal of one of the rolls to that of the opposite roll. At the outer side of each roll a pivotally-mounted arm E⁴ is mounted in air-tight relation to the casing and provided with a follow-board E⁵, contacting with the surface
 35 of the roll to insure an air-tight contact therewith. For the purpose of effecting an air-tight connection at the opposite ends of each roll any suitable packing may be used. For instance, a ring E⁶, of canvas or other flexible
 40 material, may be mounted upon the end of the roll to bear against the casing.

Beneath the feed-rollers E and removed from the suction action is the picker-roll F, having the shaft F' pivotally mounted in the
 45 casing and provided with the teeth F² of any desired character. This roll is adapted to coöperate with the concentrically-disposed screen F³, which is pivotally mounted in the casing at F⁴, so that it may be swung away
 50 from the roll for the purpose of clearing the same from clogging material or for other access to the parts, such access being conveniently had through the door F⁵ at the rear of the casing, while the material discharged
 55 through the screen is conveyed from the apparatus by means of the independently-driven feed-screw F⁶, disposed at the lower portion of the back of the casing, as shown in Fig. 1.

It has been found very desirable to provide
 60 a signal or alarm for indicating when the feed-rolls return to their contact with each other in order to indicate the finish of the operation upon any particular quantity of material or that owned by any party, while when the cot-
 65 ton is between the rolls no signal is made.

For this purpose one of the journals E' of a feed-roller is provided with a toothed or ratchet wheel E⁷, adapted to engage a pivoted striker E⁸, disposed adjacent to an alarm-bell E⁹ and held in normal position by means of a tension-spring E¹⁰. It will be seen that as the rolls separate the rotating toothed wheel will pass beyond and not engage the striker, while when the rolls again approach each other as the machine is emptied the wheel engages the 75 striker to operate the signal.

For the purpose of driving the several parts hereinbefore described a driving-pulley G is provided upon the shaft of the picker-roller F and adapted to be driven from any suitable 80 source of power. The opposite end of this roller is provided with a friction driving-plate G', of any preferred material, against which a friction-wheel G² is normally held by means of a collar G³, slidably mounted upon the free end of the shaft F' and under tension of a spring G⁴, secured to the collar and casing, as shown in Fig. 5. For the purpose of throwing the parts out of operation a shifting-lever G⁵ is pivotally mounted upon a lug G⁷, carried upon the casting G⁸, secured to the casing of the machine and bearing at its inner end upon the collar, so as to shift the same 85 away from the friction-surface G', as shown in Figs. 3 and 5. The shaft H, to which the 90 driving-wheel G² is slidably keyed, is mounted at one end in the collar G³ and at its opposite end passes through a swivel-bearing H' and is provided with a worm H². The shaft H is free to rotate within this bearing, and the pivots of the bearing are mounted in a bracket H³, carried by the casing. A movement of the friction-disk or driving-wheel G² toward or from the shaft of the picker-roll 95 varies the speed of rotation of the shaft H. For the purpose of retaining the wheel in its 100 adjusted position a collar H⁴ is secured to the wheel and embraced by a yoke H⁵, said yoke having a toothed rack-bar H⁶ extending therefrom and engaging a latching projection H⁷, carried by a fixed part. The screen-drums are driven by means of a worm-gear I, engaging the worm H² and provided upon its shaft 105 with a pinion I', meshing with the gear I², which gear is in mesh with its associate I³, so as to rotate toward each other. The shaft of each 110 of these gears is provided with a sprocket-wheel I⁴, from which a chain I⁵ extends to a similar smaller sprocket I⁶, carried upon one end of each of the feed-rolls. The feed-rolls are thus 115 driven at their proper relative speed and are also free for movement toward and from each other.

In the operation of the invention the suction from the fan A¹¹, Fig. 6, draws the cotton upward into the feed-pipe A'. From thence it is drawn downward onto the surface of the screening-drums D, being drawn in this path by the suction which passes through the drums of each feeder. The drums in 120 125

their rotation toward each other pass over the shields in their lower portion, thus cutting off the suction from the cleaned cotton, and it is dropped upon the air-tight feed-rollers E, which are normally held in contact with each other, as before described, and by their rotation feed the cotton between the same and discharge it upon the upper surface of the picker-roll F. From thence it passes over the concentric screen at one side thereof, so that sticks and other foreign matter are removed from the cotton before its delivery to the gin. The feed-rollers are provided with springs at each end, so that they may open or separate in other than parallel lines. For instance, when there is a larger feed at one end of the machine than the other that end of the rollers will separate to the greatest extent; but they are normally drawn toward each other and form with the cotton an air-tight closure in the lower portion of the suction-chamber, and thus remove from suction the picker-roll and screen, upon which the bat of clean cotton formed by the feed-rollers is discharged and is quickly and thoroughly picked in its further passage through the machine. The cut-off valve B is only used when it is desired to place the machine out of operation, while the screen-valve C below the same may be opened and closed without interfering with the suction through the machine and is adapted to hold back one body or lot of cotton until the succeeding one has passed from the machine, which is indicated by the signal device described in connection with the feed-rollers. At that time these valves are opened and the operation upon the cotton supported thereby immediately begins.

It will be observed that the throat above the screening-drums extends beyond the ends thereof and is there provided with a downwardly-inclined ledge for the purpose of feeding a greater amount of cotton to the ends of the drums. The suction connection with each of these drums is made at the end thereof next to the elevator for the feed-pipe—that is, the suction through the drums extends in an opposite direction to the feed of cotton through the pipe A'—the result of which is to secure an even layer of cotton upon the drums and permit the most effective cleaning action. The cotton under the suction-pressure as it is drawn through the feed-pipe is naturally thrown toward the left end of the drum, as shown in Fig. 2, while the connection of the suction at the opposite end counteracts this effect and secures an even delivery. The gearing disclosed provides for a continued operation of the drums and other parts which can be readily controlled as to speed or cut off whenever found desirable or necessary, while the application of the air-tight feed-rollers beneath the feed-drum insures a continuous suction feed to the picker-roll and the

screen, and thus obviates the necessity of using a trip-valve or any other device for effecting the continuous suction operating upon the other parts of the mechanism and prevents an updraft to disturb the cotton.

It will be obvious that changes may be made in the details of construction and configuration without departing from the spirit of the invention as defined by the appended claims.

Having described my invention and set forth its merits, what I claim, and desire to secure by Letters Patent, is—

1. In a gin-feeder, a casing, screening means therein, means for creating an air-feed therethrough, feed-rollers beneath the screening means disposed in contact with each other, 80 follow-boards mounted in the casing between the outer faces of the rollers and the adjacent casing to effect air-tight contact with said rollers, and means for permitting a movement of said rollers toward and from each other. 85

2. In a gin-feeder, a casing, screening means therein, means for creating an air-feed therethrough, feed-rollers beneath the screening means disposed in contact with each other, pivoted follow-boards mounted in said casing 90 to effect air-tight contact with said rollers at their free ends, and means for permitting a movement of said rollers toward and from each other.

3. In a gin-feeder, a casing, screening means 95 therein, means for creating an air-feed therethrough, feed-rollers beneath the screening means disposed in air-tight contact with the casing and with each other, a screen and picker-roll disposed beneath the feed-rollers, and 100 means carried by the screening means for preventing an air-pressure through the lower portion thereof.

4. In a gin-feeder, a casing, oppositely-disposed screening-drums located therein, a suction-fan connected with the interior of said drums, a shield disposed at the lower portion of said drums to cut off the air therethrough, and feed-rollers beneath the drums held under tension in contact with each other. 110

5. In a gin-feeder, a casing, oppositely-disposed screening-drums located therein, a suction-fan connected with the interior of said drums, a shield disposed at the lower portion of said drums to cut off the air therethrough, 115 feed-rollers beneath the drums held under tension in contact with each other, and a picker-roll and coöperating screen disposed beneath the feed-rollers.

6. In a gin-feeder, a casing, oppositely-disposed screening-drums located therein, a suction-fan connected with the interior of said drums, a shield disposed at the lower portion of said drums to cut off the air therethrough, feed-rollers beneath the drums held under tension in contact with each other, a picker-roll and coöperating screen disposed beneath the feed-rollers, pivoted arms at the opposite sides 125

of the feeding-rollers having follow-boards in contact therewith, and end packing for each of said rollers.

7. In a gin-feeder, a casing, oppositely-disposed screening-drums located therein, a suction-fan connected with the interior of said drums, a shield disposed at the lower portion of said drums to cut off the air therethrough, feed-rollers beneath the drums held under tension in contact with each other, a picker-roll and coöperating screen disposed beneath the feed-rollers, pivoted arms at the opposite sides of the feeding-rollers having follow-boards in contact therewith, end packing for each of said rollers, a partition extending partially beneath the screening-drums, and a wiper disposed above said drums in contact with the surface thereof.

8. In a gin-feeder, a casing, oppositely-disposed screening-drums located therein, a suction-fan connected with the interior of said drums, a shield disposed at the lower portion of said drums to cut off the air therethrough, feed-rollers beneath the drums held under tension in contact with each other, a picker-roll and coöperating screen disposed beneath the feed-rollers, pivoted arms at the opposite sides of the feeding-rollers having follow-boards in contact therewith, end packing for each of said rollers, a partition extending partially beneath the screening-drums, a wiper disposed above said drums in contact with the surface thereof, a pivotal mounting for one end of the picker-roll screen, and an adjustable delivery-spout disposed at the opposite end of said screen.

9. In a gin-feeder, a casing, oppositely-disposed screening-drums located therein, a suction-fan connected with the interior of said drums, a shield disposed at the lower portion of said drums to cut off the air therethrough, feed-rollers beneath the drums held under tension in contact with each other, a picker-roll and coöperating screen disposed beneath the feed-rollers, pivoted arms at the opposite sides of the feeding-rollers having follow-boards in contact therewith, end packing for each of said rollers, a partition extending partially beneath the screening-drums, a wiper disposed above said drums in contact with the surface thereof, a pivotal mounting for one end of the picker-roll screen, an adjustable delivery-spout disposed at the opposite end of said screen, a feed-pipe, and a screen-valve disposed between the feed-pipe and said drums.

10. In a gin-feeder, a casing, oppositely-disposed screening-drums located therein, a suction-fan connected with the interior of said drums, a shield disposed at the lower portion of said drums to cut off the air therethrough, feed-rollers beneath the drums held under tension in contact with each other, a picker-roll and coöperating screen disposed beneath the feed-rollers, pivoted arms at the opposite sides of the feeding-rollers having follow-boards in contact therewith, end packing for each of said

rollers, a partition extending partially beneath the screening-drums, a wiper disposed above said drums in contact with the surface thereof, a pivotal mounting for one end of the picker-roll screen, an adjustable delivery-spout disposed at the opposite end of said screen, a feed-pipe, a screen-valve disposed between the feed-pipe and said drums, and a cut-off valve at the delivery-opening of said feed-pipe.

11. In a gin-feeder, a casing provided with a throat, a suction feed-pipe communicating with the upper end of said throat, screening devices disposed at the lower end thereof, a suction-fan connected at one end of said devices to effect an air-current therethrough in a direction opposite to the feed of material through the feed-pipe, and means for releasing material from said screening devices.

12. In a gin-feeder, a casing provided with a throat, a suction feed-pipe communicating with the upper end of said throat, screening-drums disposed at the lower end thereof, a suction-fan connected at one end of said drums to effect an air-current therethrough in a direction opposite to the feed of material through the feed-pipe, a screen-valve having members pivotally mounted at opposite sides of said throat, meshing segmental gears carried by each of said members, and a coöperating lever extending from the axis of one of said gears.

13. In a gin-feeder, a casing provided with a throat, a suction feed-pipe communicating with the upper end of said throat, screening-drums disposed at the lower end thereof, a suction-fan connected at one end of said drums to effect an air-current therethrough in a direction opposite to the feed of material through the feed-pipe, a screen-valve having members pivotally mounted at opposite sides of said throat, meshing segmental gears carried by each of said members, a coöperating lever extending from the axis of one of said gears, a cut-off valve pivotally mounted below the discharge-opening from said feed-pipe, and an operating-handle extending to the pivot of said valve.

14. In a gin-feeder, a casing, a feed-pipe at the upper portion thereof, a throat extending downwardly from said feed-pipe, screening-drums at opposite sides of said throat, feed-rollers beneath said drums and in alinement with said throat, means for driving said drums and rollers, means for permitting an oscillation of the shafts of said rollers concentric to the axis of said drums, a sight-opening in said feed-pipe, a sight-opening in said casing opposite one of the screening-drums, and means adjacent to said feed-rollers for effecting an air-tight connection between the rollers and adjacent casing.

15. In a gin-feeder, a casing, a feed-pipe at the upper portion thereof, a throat extending downwardly from said feed-pipe, screening-drums at opposite sides of said throat, feed-

rollers beneath said drums and in alinement with said throat, means for driving said drums and rollers, means for permitting an oscillation of the shafts of said rollers concentric to the axis of said drums, a sight-opening in said feed-pipe, a sight-opening in said casing opposite one of the screening-drums, means adjacent to said feed-rollers for effecting an airtight connection between the rollers and adjacent casing, a picker-roll beneath said feed-rollers, a screen mounted concentric to one side of said picker-roll, a discharge-chamber beneath said screen, a conveyer connected with the lower portion of said chamber, and a door at one side of said chamber in alinement with said screen.

16. In a gin-feeder, a casing, screening-drums, feed-rollers, and picker-roll disposed therein, a friction-face secured to one end of the picker-roll, a driving-wheel having its shaft at an angle to the shaft of the picker-roll, a bearing for the lower end of said shaft slidably mounted upon the shaft of the picker-roll, means for forcing said bearing and driving-wheel toward the picker-roll, means for shifting them therefrom, and means for actuating the drums and feed-rollers from the driving-wheel shaft.

17. In a gin-feeder, a casing, screening-drums, feed-rollers, and picker-roll disposed therein, a friction-face secured to one end of the picker-roll, a driving-wheel having its shaft at an angle to the shaft of the picker-roll, a bearing for the lower end of said shaft slidably mounted upon the shaft of the picker-roll, means for drawing said bearing and driving-wheel toward the picker-roll, means for shifting them therefrom, means for actuating the drums and feed-rollers from the driving-wheel shaft, a swiveled bearing for the outer end of said shaft, and means for shifting and retaining said drive-wheel longitudinally upon the shaft.

18. In a gin-feeder, a casing, screening-drums, feed-rollers, and picker-roll disposed therein, a friction-face secured to one end of the picker-roll, a driving-wheel having its shaft at an angle to the shaft of the picker-roll, a bearing for the lower end of said shaft slidably mounted upon the shaft of the picker-roll, means for drawing said bearing and driving-wheel toward the picker-roll, means for shifting them therefrom, a swiveled bearing for the outer end of said shaft, means for shifting and retaining said drive-wheel longitudinally upon the shaft, a worm upon the free end of said shaft, and gearing extending from said worm for driving the screening-drums in opposite directions.

19. In a gin-feeder, a casing, screening-drums, feed-rollers, and picker-roll disposed therein, a friction-face secured to one end of the picker-roll, a driving-wheel having its shaft at an angle to the shaft of the picker-roll, a bearing for the lower end of said shaft

slidably mounted upon the shaft of the picker-roll, means for drawing said bearing and driving-wheel toward the picker-roll, means for shifting them therefrom, a swiveled bearing for the outer end of said shaft, means for shifting and retaining said drive-wheel longitudinally upon the shaft, a worm upon the free end of said shaft, gearing extending from said worm for driving the screening-drums in opposite directions, driving-gears upon the shafts of the feed-rollers, and means for driving said gears from said drums.

20. In a gin-feeder, a casing, screening-drums, feed-rollers, and picker-roll disposed therein, a friction-face secured to one end of the picker-roll, a driving-wheel having its shaft at an angle to the shaft of the picker-roll, a bearing for the lower end of said shaft slidably mounted upon the shaft of the picker-roll, means for drawing said bearing and driving-wheel toward the picker-roll, means for shifting them therefrom, a swiveled bearing for the outer end of said shaft, means for shifting and retaining said drive-wheel longitudinally upon the shaft, a worm upon the free end of said shaft, gearing extending from said worm for driving the screening-drums in opposite directions, driving-gears upon the shafts of the feed-rollers, means for driving said gears from said drums, means for permitting said feed-rollers to move toward and from each other concentric to the peripheries of said drums, and a tension-spring for drawing said rolls toward each other.

21. In a gin-feeder, a casing, screening-drums disposed therein, feed-rollers beneath said drums having their shafts at each end free to move toward and from each other, means for holding said rollers in contact with each other, and means for effecting a signal when said rollers are in contact.

22. In a gin-feeder, a casing, screening-drums disposed therein, feed-rollers beneath said drums having their shafts at each end free to move toward and from each other, means for holding said rollers in contact with each other, a toothed wheel carried by the shaft of one of said rollers, a pivoted striker in the path of said wheel, and an audible device adapted to be contacted by said striker.

23. In a gin-feeder, a casing, screening-drums disposed therein, feed-rollers beneath said drums having their shafts at each end free to move toward and from each other, means for holding said rollers in contact with each other, a toothed wheel carried by the shaft of one of said rollers, a pivoted striker in the path of said wheel, an audible device adapted to be contacted by said striker, sprocket-wheels carried by the shaft of said feed-rollers at one end, sprockets carried by the shafts of the screening-drums, chains extending between said sprockets, and means for rotating said screening-drums toward each other.

24. In a gin-feeder, screening-drums, feed-

rollers beneath the same mounted for lateral movement toward and from each other in arcs having their centers at the axes of the drums, and means for retaining said rollers in contact 5 under tension.

25. In a gin-feeder, a casing, screening means, feed-rollers beneath the same mounted for lateral movement toward and from each other, means for retaining said rollers in contact under tension, and a packing carried by the end of said rollers to contact with said casing.

26. In a gin-feeder, a casing having a suction-chamber therein, opposite screening devices in said chamber, continuously-operating opposite feed-rollers disposed beneath and intermediate of said devices and constructed and arranged to effect an air-tight closure with the casing and prevent an upward draft of air therethrough, and means for releasing material from the screens for delivery to the rollers.

27. In a gin-feeder, a casing having a suction-chamber therein, a screening device in said chamber, continuously-operating feeding means disposed beneath said device and con-

structed and arranged to effect an air-tight closure beneath the screening device and prevent an upward draft of air through the casing, and means coöperating with the screening device to release material therefrom for deposit upon the feeding means.

28. In a gin-feeder, a casing having a suction-chamber therein, a screening device in said chamber, continuously-operating feeding means disposed beneath said device and constructed and arranged to effect an air-tight closure beneath the screening device and prevent an upward draft of air through the casing, means coöperating with the screening device to release material therefrom for deposit upon the feeding means, a feed-pipe communicating with said chamber, and a suction device communicating with said screening device to maintain a continuous suction through said chamber.

In testimony whereof I affix my signature in presence of two witnesses.

JOHN W. SEIFERT.
